(57) **CLAIM**

The ornamental design for a portable power tool with dieless tool head, as shown and described.

DESCRIPTION

FIG. 1 is a top, front, and right side perspective view of a portable power tool with dieless tool head showing our new design in accordance to a first embodiment;

FIG. 2 is right side elevation view thereof;

FIG. 3 is a left side elevation view thereof;

FIG. 4 is a front elevation view thereof;

FIG. 5 is a rear elevation view thereof;

FIG. 6 is a top plan view thereof; and

FIG. 7 is a bottom plan view thereof.

FIG. 8 is a top, front, and right side perspective view of a portable power tool with dieless tool head showing our new design in accordance to a second embodiment;

FIG. 9 is right side elevation view thereof;

FIG. 10 is a left side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The broken lines in the drawings illustrate portions of the portable power tool with dieless tool head that form no part of the claimed design.
